UNITED STATES PATENT OFFICE.

JAMES HENRY BRADY, OF LOUISVILLE, KENTUCKY.

CEPHALIC BAND.

1,250,273.

Specification of Letters Patent. Patented Dec. 18, 1917.

Application filed June 26, 1916. Serial No. 105,821.

To all whom it may concern:

Be it known that I, JAMES HENRY BRADY, a citizen of the United States, and a resident of Louisville, in the county of Jefferson and 5 State of Kentucky, have invented a new and Improved Cephalic Band, of which the following is a specification.

This invention relates to a band of new and useful construction, peculiarly contoured 10 to fit about the head, being disposed across the brow and over the temples, and is adapted to be used for the alleviation of headache.

Headache is caused largely by increased blood pressure, the underlying causes of the 15 increased pressure being various.

Pain may be alleviated by decreasing the quantity, or pressure of blood supplied to the afflicted part. This may be accomplished in many ways, among which may be mentioned 20 pressure applied to, or over the artery supplying blood to the part, the application of a counter irritant to a circumscribed area, which by dilating the subcutaneous blood vessels will provide storage for a quantity 25 of blood that would otherwise go to the afflicted part.

Pressure applied to the nerve leading to the afflicted part also serves to deaden the pain.

30 Pressing the temples with the hands to relieve headache is done instinctively by many people without knowing why it relieves the ache. A handkerchief is frequently tied around the head for the same 35 purpose but does little good because it does not reach down low enough on the temples unless tied over the eyes and will not exert pressure at the proper point even then.

An object of this invention is to provide 40 means whereby pressure may be exerted upon the temporal artery and the temporal nerve thereby diminishing the supply of blood to the head and deadening the sensation of pain.

45 Another object is the provision of means for applying a medicament to the brow and temples.

A further object is the provision of a band shaped to fit the contour of the head 50 and be comfortable to the wearer.

A still further object is the provision of a band containing pressure elements which may be adjusted so as to lie in the hollow of the temples.

With the foregoing and other objects in view, the invention consists of the novel construction and arrangement of parts illustrated in the accompanying drawing, which forms a part of this specification wherein is set forth an embodiment of the invention, 55 but it is to be understood that such changes and modifications may be resorted to as come within the scope of the appended claims.

Referring to the drawing, wherein similar reference characters designate like parts in the several views, Figure 1, is a side elevation of an embodiment of the device, a portion being broken away to show the pressure disk: Fig. 2, a section on line 2-2 of 60 Fig. 1: Fig. 3, a section on line 3-3 of Fig. 1: Fig. 4, a side elevation of one of the adjustable pressure disks: Fig. 5, a central transverse section of said disk.

The invention consists of a band —10— 65 adapted to be applied to the head for the alleviation of headache, and comprises a central portion, or body —11— arcuate in shape, so that when applied to the forehead, just above the eyes, it will conform 70 to the curvature of the head, extending across the brow and downward at each end in line with the temples. Attaching members, or straps —12— extend from each end of the central portion at such an angle there- 75 to that when the band is in position said straps pass over the temples and about the head, just above the ears. Suitable means such as a buckle —13— is provided for connecting the free ends of the straps and draw- 80 ing them together to exert the desired pres- 85 sure. The band may be constructed of any suitable material; however I prefer to make it of felt, as it is non-elastic, thereby retain- 90 ing its shape, is very absorbent, thereby be- 95 ing a good medium for carrying a liquid medicament, and is easily washed. The band is preferably formed of two layers —14,

15— of material united by any suitable means, but preferably by a marginal line of 100 stitching —16—, thereby forming a sub- 105 stantially tubular structure. The stitching extends along the lower, or concave edge of the body and along both edges of the straps, but not along the upper or convex edge —17— of the body, which is left open to afford access to the interior. An enlargement —18— at the juncture of the strap

with the body forms a pocket —19— within which may be placed pressure members —20—. The pressure member is preferably a double convex disk, preferably formed of 5 felt, and of such size as will lie comfortably in the hollows of the temples. The pockets are elongated in order that the disks may be adjusted to and fro therein to suit heads of different sizes.

10 In service, the band is placed against the forehead with the lower edge of the body portion just above the eyebrows, the pressure disks shifted until they lie in the hollows of the temples. The ends of the straps 15 are then drawn together, until a comfortable pressure is felt, and secured. If desired, the disks may be saturated with a medicament, such as camphor. The disks being of felt, which is a resilient substance, insures that 20 a harmful pressure will not be exerted upon the artery or nerve.

Having thus described my invention so

that anyone may make and use the same, I claim:

1. A cephalic band adapted to be disposed 25 about and conform to the head, said band comprising a casing having an arcuate central, or body portion, straps or fastening members integral with the body, extending from convex side thereof, elongated pockets 30 in proximity to the juncture of the straps with the body and convex resilient disks adjustably positioned in said pockets.

2. A cephalic band adapted to be disposed about and conform to the head, said band 35 comprising a casing having an arcuate central or body portion, straps or fastening members integral with the body, extending from convex sides thereof, elongated pockets 40 in proximity to the juncture of the straps with the body and convex absorbent pads adjustably positioned in said pockets.

JAMES HENRY BRADY.
